attorney.

UNITED STATES PATENT OFFICE.

HENRY C. WEEDEN, OF BOSTON, MASSACHUSETTS.

AUTOMATIC FLUSHING DEVICE.

SPECIFICATION forming part of Letters Patent No. 415,260, dated November 19, 1889.

Application filed March 18, 1889. Serial No. 303,172. (No model.)

To all whom it may concern:

Be it known that I, HENRY C. WEEDEN, of Boston, in the county of Suffolk and State of Massachusetts, a citizen of the United States, 5 have invented certain new and useful Improvements in Automatic Flushing Devices for Urinals, of which the following is a specification.

My present improvement relates to that 10 class of devices for producing an automatic flush of the bowl of a urinal or similar structure whenever the same is used, in which devices a siphon flushing-pipe extending from the supply-tank to the bowl to be flushed is 15 set in operation by means of rarefaction of the air in the long leg of the siphon, this rarefaction being produced through the instrumentality of an air-exhaust pipe extending downwardly from a point in the long leg to a 20 point below the urinal-bowl.

The object of my invention is to improve the construction of the specific devices whereby by the passage out from the urinal-bowl of liquid introduced therein when the bowl is 25 used produces the exhaustion or rarefaction of air in the long limb of the siphon.

In the accompanying drawing I have represented in vertical section and elevation a device embodying my present improvement. 30 In the drawing, A represents the tank; B, the siphon flushing-pipe; C, the bowl to be flushed; D, the outlet thereof, and E the air-exhaust pipe.

In the operation of my improved structure 35 the rarefaction or exhaustion of air is obtained by causing the fluid from the urinal to pass in the form of a jet through a body of air with which the exhaust-pipe connects, and past its mouth. I accordingly form at a convenient point below the bowl a contracted or 40 jet orifice F, as shown. The exhaust-pipe, as shown, in order to produce the best results, should enter the discharge-pipe D just below the point where the jet leaves the orifice 45 F. As this orifice, to produce the best results, should be of small diameter relatively to the whole bore of the discharge-pipe, I provide a branch or supplement G of the discharge-pipe of a caliber sufficient to carry off 50 the flushing water, and I prefer to trap this branch G as well as the pipe D. If not so trapped, it is obvious that a passage-way

would be left for gases from the drain to the apartment.

As the operation of the device will be found 55 to depend somewhat upon the relative caliber of the various pipes, I will state that good results will be obtained by giving to the supply-pipe B a diameter of three-fourths of an inch, and to the discharge-pipe D, where it 60 leaves the bowl, a diameter of one and one-quarter inch, to the exhaust-pipe a diameter of one-fourth of an inch, to the jet-orifice a diameter of one-eighth of an inch, and to the branch pipe G a diameter of one and one-fourth inch. 65

The operation of the parts is as follows: The drawing representing the parts at rest, if fluid be introduced into the bowl of the urinal, it will pass down into and back up 70 within the contracted portion of the discharge-pipe above the jet-orifice, and will escape therefrom forcibly in the form of a jet. This jet passes through the body of air which lies within the discharge-pipe below the jet-orifice and around the mouth of the exhaust-pipe, and produces a rarefaction or exhaustion 75 of the air therein, and this in turn rarefies or exhausts the air in the long leg of the siphon, and thus starts its flow. When the 80 flushing water descends, it will pass off partially through the jet-orifice, but mainly through the branch pipe G, and thence through the discharge-pipe to the sewer.

I claim—

85 In a device for causing the automatic flushing of the bowl of a urinal or similar structure, the combination, with said bowl, its supply-tank, and siphon flushing-pipe, of a discharge-pipe leading downwardly from the 90 bowl and having a jet-forming orifice located therein, an air-exhaust pipe extending from the long leg of the siphon flushing-pipe down to and entering the discharge-pipe below the jet-forming orifice, and an auxiliary or branch 95 discharge-pipe G, all substantially as set forth.

In testimony whereof I have hereunto subscribed my name this 9th day of March, A. D. 1889.

HENRY C. WEEDEN.
